[57] CLAIM

The ornamental design for a dry shaver, as shown and described.

DESCRIPTION

FIG. 1 is a perspective view showing my new design with the cover removed for a complete disclosure of the underlying parts;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is an exploded perspective view; and,

FIG. 9 is a perspective view of the fully assembled design. The portions of the brush and cover that cannot be seen in FIGS. 8 and 9 are not claimed as part of my new design.
